UNITED STATES PATENT OFFICE

138,332

DESIGN FOR AN EARRING

Clifford A. Furst, New York, N. Y.

Application June 8, 1944, Serial No. 113,911

Term of patent 7 years

(Cl. D45—9)

To all whom it may concern:

Be it known that I, Clifford A. Furst, a citizen of the United States of America, residing in New York, county of New York, and State of New York, have invented a new, original, and ornamental Design for an Earring, of which the following is a specification, reference being had to the accompanying drawing, forming part thereof.

Fig. 1 is a plan view of an earring showing my new design.

Fig. 2 is an edge view thereof.

I claim:

The ornamental design for an earring, substantially as shown.

CLIFFORD A. FURST.
